UNITED STATES PATENT OFFICE.

TERELIUS A. HILL, OF MARYVILLE, TENNESSEE.

GATE.

SPECIFICATION forming part of Letters Patent No. 739,870, dated September 29, 1903.

Application filed April 15, 1903. Serial No. 152,731. (No model.)

To all whom it may concern:

Be it known that I, TERELIUS A. HILL, a citizen of the United States, residing at Maryville, in the county of Blount and State of 5 Tennessee, have invented a new and useful Improvement in Gates, of which the following is a specification, reference being had to the accompanying drawings.

My improvement relates to gates which extend across roadways or entrances to buildings or other similar passages.

The invention has reference particularly to gates which are supported at one end upon a hinge which is vertical and in a plane parallel 15 to the plane of the gate.

The object of the invention is to produce such a gate which may be cheaply made and which shall embody mechanism adapted to operate in a simple manner.

20 In the accompanying drawings, Figure 1 is a side elevation of the gate when the latter is closed. Figs. 2, 3, and 4 are detail views of the mechanism whereby the gate-shifting arm is secured to the gate. Fig. 5 is a plan showing the gate in the closed position. Figs. 6, 25 7, and 8 are details of the upper hinge of the gate.

Referring to said drawings, A is the gate proper. This is shown composed of the top 30 rail A¹, bottom rail A², outer upright A³, and inner upright A⁴.

B is a post to which the gate is hinged. Said post has horizontal brackets B' and B². Said brackets have vertical eyes, and the gate has 35 on the upper portion of the upright A⁴ a bracket A⁵, having a depending lug a⁵ extending into the eye of the bracket B', and the bracket A⁶ is located upon the lower inner portion of the gate and has a lug a⁷ rising through the eye of the bracket B². These 40 four brackets form the hinge for the gate, the upper brackets sustaining the gate against downward movement and the lower brackets holding the gate against upward movement.

45 C is a post for holding the free end of the gate when the latter is in the closed position. Said post is preferably set in such position as to permit the outer upright A³ of the gate to bear against said post.

50 An L-shaped latch-bar C' has one arm extending horizontally through the upright A³ from the outer face of the latter toward the

inner or hinge end of the gate, and said arm is pivoted to said upright at C². The other arm of said bar extends downward along the 55 outer face of the upright A³. A wire or cord C³ extends from the free end of said horizontal arm toward the inner upright A⁴, where it is secured to the hook of a hook-bolt C⁴, extending through said upright A⁴. The arms 60 of said latch-bar meet each other at a little more than a right angle, so that tension on the wire or cord C³ will tilt said latch-bar upon its hinge and move the lower end of the latch-bar away from the gate. The tension 65 of said wire or cord C³ may be varied by turning the nut on said hook-bolt, and said tension is preferably sufficient to cause the latch-bar C' to tilt into its normal position, said bar in so tilting drawing the wire F², whereby the 70 bar D is moved into its normal position.

A hook C⁵ extends horizontally from the post C in a line perpendicular to the plane of the gate and in the direction of movement of the gate when the latter opens, and said hook 75 extends far enough toward the upright A³ of the gate to extend across the path traversed by the latch-bar when the gate swings and the lower end of the latter is in its normal position—in its position farthest from the upright A³. Said hook C⁵ therefore prevents the opening of the gate unless the lower end of the latch-bar be first drawn toward the upright A³ enough to clear said hook C⁵. The shifting of said latch-bar preparatory to the 80 opening of the gate is performed automatically through the action of the L-shaped shifting-bar D, attached to the inner upright A⁴ of the gate. Said shifting-bar has the upright arm d and the horizontal arm d'. Said 85 horizontal arm is located at the side of the gate opposite the direction in which the gate is to move while opening, and said arm stands at an angle of about forty-five degrees to the plane of the gate. The lower end of the arm 90 d is hinged to the bracket E, the latter being supported by the upright A⁴. At a short distance above said bracket E a guide-bracket F is secured to the upright A⁴. Said guide-bracket has a vertical slot F', through which 95 the arm d extends. The hinge of the bracket E and the slot F' in said bracket F are so positioned as to permit movement of the arm d only in a plane which is vertical and radial.

to the hinge of the gate. It will be seen that such movement of the bar D will involve its approaching and receding from the outer upright A⁴. Hence a wire or cord F², attached by one end to the bar D and by the other end to the upright arm of the latch-bar C', will cause said arm to move toward the hinge end of the gate when the bar D is moved toward the upright A⁴, (to the left as shown in Fig.

10 1.) It follows that any suitable mechanism may be used for moving said bar D upon its hinge to cause the movement of the latch-bar out of the range of the hook C⁵. In the construction herein shown the bar D is used for shifting the latch-bar and also for turning the gate after the latch-bar has been shifted.

15 G G are posts located at the side of the roadway and at opposite sides of and substantially in line with the hinge-post B. Said posts G support suitable cord-guides—as, for example, pulleys G'—by any suitable means, as by arms G², extending toward the roadway into line with the free end of the horizontal arm d' of the bar D. A cord H extends from said 20 horizontal arm d' to and around one of said pulleys and thence to and around the other of said pulleys and thence back to said horizontal arm, said cord being secured to said arm in any suitable manner.

25 30 When the gate is closed, the operation of opening is as follows: The section of the cord extending directly from pulley to pulley is grasped and pulled in the direction opposite the direction in which the gate is to move, or the portion of the cord between the horizontal arm d' and the pulley at the opposite side of the gate may be drawn in the direction of said pulley. This results in first drawing the upper end of the arm d' toward the adjacent 35 upright A⁴ and correspondingly shifting the wire F² and the adjacent latch-bar C' so that the latter is brought out of engagement. Now continued pulling on said cord causes the swinging of the gate by means of the 40 strain exerted upon said horizontal arm d'. 45

I is a stop-post located at the side of the roadway approximately in line with the posts G and B and at the same distance from the hinge of the gate as the outer post C is located from said hinge, and said post I has a hook I' similar to the hook C⁵ on the post C and suitably positioned to engage the latch-bar C' when the gate swings against said post I.

50 55 To close the gate, the movement already described for its opening is reversed, the pulling on the cord in the reverse direction again first releasing the latch-bar and then swinging the gate.

60 65 Fig. 4 shows in detail a convenient form of construction for the hinge-bracket E. A plate E' has a slot E² for receiving a bolt E³, extending into the upright A⁴, for securing said plate to said upright. Said plate is provided at the end the farther from the gate-hinge with an extension E⁴, standing at an angle of approximately forty-five degrees to

the plane of the gate. Two plates E⁵, similar to the members of an ordinary journal-box, surround the upright arm of the shifting-bar D, said plates being adapted to be clamped immovably against the exterior of said arm. The extension E⁴ is located between the two adjacent ends of the plates E⁵, and a bolt E⁷ extends through said extension and said plates. A bolt E⁸ extends transversely through the opposite ends of said plates. By properly tightening said bolts said plates are clamped immovably to the bar D. Said bolts may be best adjusted by first 80 tightening E⁷ and then tightening E⁸ sufficiently to bind said plates to the bar D. This leaves said plates free to turn upon the plate E', although they are firmly bound to the bar D. Preferably the faces E⁶ at one end of the 85 pair of plates E⁵ are farther separated than at the other end of said plates in order to adapt said plates to bars D of different thicknesses. As shown in the drawings, the faces E⁶ which are the nearer to each other are applied to the extension E⁴. This leaves the clamping-plates farther from each other than would be the case if their opposite ends were applied to such extension, and this adapts the plates for binding to a relatively thick 90 bar D. As put together in the drawings, the bar D is, for example, of a diameter of an inch and a quarter, while the clamp-plates may be applied to a bar having a diameter of one inch if such plates be reversed. The 95 slot E² permits the horizontal movement of the plate E' upon the bolt E³ for the purpose of effecting a horizontal adjustment of the bracket E and the bar D. By loosening the bolts E⁷ and E⁸ the bar D may be moved vertically to secure any desired adjustment. Horizontal adjustment of the horizontal arm d' of the bar D may be further effected by loosening said bar in the bracket E and rotating it to any desired extent. The plate E' 100 is also provided with a transverse aperture e', which may receive one arm of a U-bolt, the other arm going through the slot E² and surrounding the upright A⁴ when the latter is cylindric, as illustrated in Fig. 2.

115 Fig. 3 illustrates in detail the gate-bracket F. As already stated, the slot F' in said bracket receives the upright arm d of the shifting-arm D. Said slot is preferably substantially radial to the hinge of the gate and at an angle corresponding to the angle of the hinge-bracket E. The base of the bracket F has a slot F³ and an aperture F⁴, corresponding to the slot E², and an aperture e' in the hinge-bracket used for the same purposes.

120 125 If the gate is to swing in the direction opposite that shown in the drawings, the brackets E and F and the bar D are placed upon the opposite side of the gate on the corresponding outer corner of the upright A⁴, and when so desired the bar D may be directed away from instead of toward the free end of the gate. This is accomplished by placing the brackets E and F upon the cor-

ner of the upright A⁴ diagonally opposite the corner shown in the drawings; but the hinge-bracket and the guide-bracket must then be transposed and the latch-cord applied to the bar D below the hinge-bracket, for the portion of said bar below its hinge will then move away from the latch when the gate is to be opened. Said transposition of said brackets may be readily made, for their bases are alike.

10 Thus the simple parts described are adapted to secure the bar D in any one of four general radial positions—to vary the particular radial angle of said bar, to vary the elevation of said bar, to vary the size of said bar, and 15 to attach said bar to end uprights A⁴ of different forms. This adaptation to make these several variations is of great practical importance.

10 The bracket A⁵, which forms a part of the 20 gate-hinge, is shown in detail in Figs. 6, 7, and 8. Said bracket consists of the horizontal portion a¹, having the horizontal slots a², a vertical arm a³, having a horizontal aperture a⁴, and a depending cylindric lug a⁵.

25 Bolts a⁶ extend through the slots a², and a similar bolt may likewise extend through the aperture a⁴ into the upright A⁴ to secure said bracket. The horizontal portion of said bracket is long enough to project beyond each 30 lateral face of the upright A⁴, so as to permit the insertion of a hook-bolt J through the outer portion of each of the slots in said bracket. Said hook-bolts have their hooks directed toward the free end of the gate, and 35 brace-wires J' extend from the lower outer portion of the gate diagonally upward to and into engagement with said hooks. By means of said hook-bolts any desired tension may be put upon said brace-wires.

40 I claim as my invention—

1. The combination with a gate secured by a vertical hinge to an upright post, of a member extending laterally from the plane of said gate and hinged to adapt it to move radially 45 to the hinge of the gate, a guide-bracket for limiting the movement of said member, latch mechanism at the free end of said gate, mechanism extending from said latch mechanism to said member, and means for applying force 50 to said member to cause the latter to move so as first to release the latch and then move the gate.

2. The combination with a gate secured by a vertical hinge to an upright post, of a member extending laterally from the plane of said gate, and hinged to adapt it to move radially to the hinge of the gate, an adjustable guide-bracket for limiting the movement of said member, latch mechanism at the free end of 55 said gate, mechanism extending from said latch mechanism to said member, and means for applying force to said member to cause the latter to move so as first to release the latch and then move the gate.

60 3. The combination with a gate secured by a vertical hinge to an upright post, of a guide-

bracket and a hinge-bracket, both secured to the gate near the hinge of the latter; a bar, D, hinged to said hinge-bracket to permit movement in a plane radial to the hinge of 70 the gate, and extending through said guide-bracket, latch mechanism at the free end of said gate, mechanism extending from said latch mechanism to said bar, and means for applying force to said bar to cause the latter 75 to move so as to release the latch and then move the gate.

4. The combination with a gate secured by a vertical hinge to an upright post, of a bracket secured to the gate near the hinge of 80 the latter, said bracket consisting of a portion immovably secured to the gate and a second portion hinged to said first-mentioned portion at a suitable angle to permit movement in a plane radial to the hinge of the 85 gate, a bar secured to the hinged portion of said bracket, latch mechanism at the free end of said gate, mechanism extending from said latch mechanism to said bar, and means for applying force to said bar to cause the latter 90 to move so as first to release the latch and then move the gate.

5. The combination with a gate secured by a vertical hinge to an upright post, of a guide-bracket and a hinge-bracket each secured to 95 the gate near the hinge of the latter, said hinge-bracket consisting of a portion immovably secured to the gate and a second portion hinged to said first-mentioned portion at a suitable angle to permit movement in a 100 plane radial to the hinge of the gate, a bar secured to the hinged portion of said hinge-bracket, latch mechanism at the free end of said gate, mechanism extending from said latch mechanism to said bar, and means for 105 applying force to said bar to cause the latter to move so as first to release the latch and then move the gate.

6. The combination with a gate secured by a vertical hinge to an upright post, of a 110 bracket secured to the gate near the hinge of the latter, said bracket consisting of a plate immovably secured to the gate and two plates hinged to said plate at a suitable angle to permit movement in a plane radial to the 115 hinge of the gate, a bar clamped by said plates, latch mechanism at the free end of said gate, mechanism extending from said latch mechanism to said bar, and means for applying force to said bar to cause the latter to move 120 so as first to release the latch and then move the gate.

7. The combination with a gate secured by a vertical hinge to an upright post, of a bracket secured to the gate near the hinge of 125 the latter, said bracket consisting of an oblique-ended plate immovably secured to the gate and two clamp-plates, E⁵, bolts, E⁷ and E⁸, the bar, D, clamped between said plates, latch mechanism at the free end of said gate, 130 mechanism extending from said latch mechanism to said bar, and means for applying

force to said bar to cause the latter to move so as first to release the latch and then move the gate.

8. The combination with a gate secured by 5 a vertical hinge to an upright post, of a bracket secured to the gate near the hinge of the latter, said bracket consisting of a plate immovably secured to the gate and two clamp-plates, E⁵, bolts, E⁷ and E⁸, the bar, D, clamped 10 between said plates, the plates, E⁵, having faces, E⁶, separated from each other farther at one end of said pair of plates than at the other end, latch mechanism at the free end

of said gate, mechanism extending from said latch mechanism to said bar, and means for 15 applying force to said bar to cause the latter to move so as first to release the latch and then move the gate.

In testimony whereof I have signed my name, in presence of two witnesses, this 10th 20 day of April, in the year 1903.

TERELIUS A. HILL.
